US0D1098011S

(12) **United States Design Patent** (10) Patent No.: **US D1,098,011 S**
(45) Date of Patent: ** Oct. 14, 2025

(54) **HOME CHARGING PILE KIT**

(71) Applicant: **NIO TECHNOLOGY (ANHUI) CO., LTD**, Hefei (CN)

(72) Inventors: **Jingyang Yao**, Shanghai (CN); **Maxime Le Ruyet**, Shanghai (CN); **Zilin Chen**, Shanghai (CN); **Kechao Li**, Shanghai (CN); **Kris Tomasson**, Munich (DE); **Colin Phipps**, Shanghai (CN); **Shiyi Hang**, Shanghai (CN); **Long Sheng**, Shanghai (CN); **Sichuan Huang**, Shanghai (CN); **Haibin Zhao**, Shanghai (CN); **Lijian Xia**, Shanghai (CN); **Xiang Zhang**, Shanghai (CN)

(73) Assignee: **NIO TECHNOLOGY (ANHUI) CO., LTD**, Hefei (CN)

(**) Term: **15 Years**

(21) Appl. No.: **29/954,994**

(22) Filed: **Jul. 30, 2024**

CLAIM

The ornamental design for the home charging pile kit as shown and described.

DESCRIPTION

FIG. 1 is a perspective view of a handle receiver of home charging pile kit;

FIG. 2 is a front elevation view thereof;

FIG. 3 is a left side elevation view thereof;

FIG. 4 is a right side elevation view thereof;

FIG. 5 is a rear elevation view thereof;

FIG. 6 is a top plan view thereof; and,

FIG. 7 is a bottom plan view thereof.

1 Claim, 4 Drawing Sheets
